19 Claims. (Cl. 171—229)

The present invention relates to electrical arrangements for controlling the voltage of current from a source of electric potential subject to fluctuations in voltage, whereby the fluctuations in voltage at the source will not be impressed across apparatus to be operated by such current. There are many instances where a constant voltage is necessary for the operation of mechanism, such as fire detecting apparatus, smoke detecting apparatus, etc. yet the location of the apparatus frequently is such that a current supply of this character is not available. Thus, by way of example, in the use aboard ship, where wide variations in the voltage of the source of electric potential are known to be a common occurrence, of smoke detecting apparatus of the type employing a source of light directed upon a light-sensitive element with a current of air flowing along the path of the beam of light directed from the source of light upon the light-sensitive element and in which the presence of smoke in the current of air acts to decrease the intensity of the light falling upon the light-sensitive element and to thereby cause an alarm signal to be rendered, it has been found that if the light-sensitive element circuit has been adjusted to give detection for a reasonably light smoke density, it will also give false alarms for a drop in the line voltage as little as four volts, it being understood that a drop in the line voltage will cause a decrease in the intensity of the light emitted by the source of light. For this reason a well designed smoke detecting apparatus of the type referred to requires a voltage regulator to be used on the source of light to prevent fluctuations in the voltage applied thereto regardless of the changes in voltage at the source of electric potential.

It is accordingly the principal object of the present invention to provide means for controlling the voltage of current from a source of electric potential to maintain a constant value thereof across desired terminals, in spite of relatively great variations of the voltage at the source.

It is also an object of the invention to provide a constant voltage across desired terminals despite not only variations of the voltage at the source of electric potential but also variations in the load applied across the aforesaid terminals.

It is a further object of the invention to provide signalling means to indicate when the variations in the voltage at the source are so great that the apparatus of the present invention will not bring the load voltage back to normal, so that proper steps may be taken at once to correct the voltage directly at the source.

These, and other objects of the invention not specifically enumerated above, will be apparent as the invention is described in greater detail in connection with the accompanying drawings, where-
in:

Figure 7 is a simplified conventional view showing an adaptation of the present invention to controlling the output voltage of an electric generator. 25

Figure 8 is a simplified conventional view showing an adaptation of the present invention to controlling the speed of an electric motor.

In order to simplify the explanation of the circuit of the complete voltage regulating arrangement of Figure 1, reference will first of all be made to the simplified showing of Figure 2, in connection with which it should be noted that the regulator circuit is a special type of Wheatstone bridge in which, for example, two neon glow tubes are used instead of resistances. These are shown at G and T. These neon glow tubes have as an important characteristic the ability to automatically change their resistance so as to maintain the voltage constant across their terminals. 30 Thus in the circuit shown in Figure 2, when the current is flowing from e through resistance X through glow tube G to O, the voltage across glow tube G remains constant regardless of changes in voltage across points O and e (within 35 limits). 40

Neon glow tubes may be obtained for various voltages, but for the purpose of the present explanation it will be assumed that the voltage maintained by the glow tubes is in the order of 50 60 volts, varying slightly for different tubes due to manufacturing variations. Also the voltage at O will be considered the datum point of zero and all voltages are referred to the voltage at O. 45

Therefore, in Figure 2, current flows from the 55

positive unregulated line E through a rheostat W to point e, flowing to negative through resistance X and glow tube G, which is paralleled by a series of resistances Y, to O. Current also flows from 5 e through glow tube T, through resistance Z, to O. Since the voltage drop across the glow tubes is 60 volts, the voltage at M will be 60 volts, while the voltage at F will be 60 volts less than that at e. As the unregulated voltage at E varies, the 10 voltage at e will likewise vary, and due to the constant voltage drop across glow tube T the voltage at F will also vary the same amount. The voltage at M, however, will remain constant regardless of any variation of voltage E. Since 15 the voltage at M is constant, the voltage at any point S of the series of resistances Y will also be constant. If it is desired to maintain a voltage at e of 90 volts, the voltage at F will be 30 volts. Since the voltage at S is constant, an adjustment 20 may be made to cause this voltage to be 30 volts. If a galvanometer relay G. R. is now connected between S and F, there will be no voltage difference across G. R. and the galvanometer pointer will float clear of its contacts. If, however, the 25 voltage at E rises, the voltage at e will also rise and the voltage at F will rise equally. Since the voltage at S remains constant, the galvanometer pointer will be deflected against one of its contacts, which action can be employed (as will be 30 explained in connection with Figure 1) to effect increases or decreases in the amount of the resistance of the rheostat W in circuit. Therefore, upon the aforesaid rise in the voltage at E, the resistance W is increased and the voltage at e 35 will decrease until the voltage at F is 30 volts, when the galvanometer will be neutral. When the voltage at F is 30 volts, the voltage at e will will be 90 volts, which is the desired regulated voltage. The reverse operation takes place when 40 the unregulated voltage at E decreases.

By way of example (neglecting the small voltage drop caused by the flow of current through the galvanometer relay when unbalanced), if the voltage at E were 110; at e, 90; at S, 30; and at 45 F, 30; the galvanometer would be balanced. If the unregulated voltage then became 113 at E, the voltage at e would be 93 and at F, 33, the voltage at S remaining at 30. Consequently, the change in unregulated voltage of 3 volts from normal is 50 transmitted directly to the galvanometer relay, resulting in the adjusting operation as just described.

Of course, with reference to Figure 2, the apparatus on which it is desired to maintain a constant voltage is connected across the terminals L₁ and L₂.

Referring now to the circuit of the complete voltage regulating arrangement shown in Figure 1, the same reference characters as were employed in connection with Figure 2 have been used wherever possible. However, the resistances A, B, C and D together comprise the series of resistances shown in Figure 2 as Y. The unregulated voltage is applied from the positive POS. 65 of the source of electric potential to the terminal line E and from the negative NEG. to the terminal line O. The regulated positive voltage is obtained from terminal line L₁, the negative line being shown at L₂. When the voltage across terminals 70 E and O drops, galvanometer relay G. R. deflects to the left, causing the relay 1 to operate through a circuit from negative terminal line O, through resistance 2, through the now closed contact 3, through the relay 1, through the normally closed 75 contact 4, and through wires 5, 6 and 7 to the posi-

tive terminal line E, causing the relay 1 to operate. The operation of the relay 1 closes the contact 8, permitting a current to flow from the positive terminal line E, through wires 7, 6 and 9, through contact 8, through armature 10, through wires 11 and 12, through the field 13 of the voltage regulator motor 14, through wires 15, 16 and 17 to the negative terminal line O. Closing of the contact 18 of the relay 1 permits current to flow from positive terminal line E, through wires 10 7, 6, 5 and 19, through armature 20, through contact 18, through the relay 21, through the resistance 22, and through wire 17 to the negative terminal line O, causing the relay 21 to operate. Current then flows from the positive terminal line E, through wires 7, 6 and 9, through contact 8 of the relay 1, through armature 10, through wires 11 and 23, through armature 24 of the relay 21, through the now closed contact 25, through resistance 26, through wire 27, through the armature of the voltage regulator motor 14, through the wire 28, through the now closed contact 29 of the relay 21, through the armature 30, and through wires 16 and 17 to the negative terminal line O. Since both the armature and the field 13 25 of the voltage regulator motor 14 are now connected to positive and negative, this motor causes the motor driven rheostat W to turn so as to reduce its resistance and bring the regulated voltage at terminal L₁ (e) to its proper value. When 30 the voltage at terminal L₁ (e) is correct, the contacts of the galvanometer relay G. R. clear, releasing the relay 1 and the relay 21, permitting the voltage regulator motor 14 to stop. When the voltage across terminals E and O increases, 35 the galvanometer relay G. R. deflects to the right, causing the relay 31 to operate through a circuit from the negative terminal line O, through resistance 2, through the now closed contact 32, through the relay 31, through the normally closed 40 contact 33, through wires 34 and 7 to the positive terminal line E. The operation of the relay 31 closes the contact 35, permitting a current to flow from positive terminal line E, through wires 7, 34 and 36, through armature 37 of the relay 45 31, through contact 35, through wire 12, through field 13 of the voltage regulator motor 14, and through wires 15, 16 and 17 to negative terminal line O, thus energizing the field 13 in exactly the same sense as it is energized by operation of the 50 relay 1. However, the relay 21 is not energized upon operation of the relay 31 (as it is upon operation of the relay 1), so that the direction of the current through the armature of the voltage regulator motor 14 is reversed, causing the motor 55 to turn in the opposite direction and to bring the regulated voltage at terminal L₁ (e) to its proper value. In accomplishing this, the connection from the positive terminal line E is through the contact 38 of the relay 21 to the wire 28 connecting 60 to one side of the armature of the motor 14, instead of through contact 25 of the relay 21 to the wire 27 connecting to the other side of the armature of the motor 14. 65 It should be noted that resistance 26 is provided to reduce the speed of the voltage regulator motor 14 and to prevent arcing of the contacts of the relay 21. 70 It will be noted that the relay 31 operates when the unregulated voltage increases. Operation of this relay not only causes the contact at 35 to be closed, as already explained, but at the same time causes the contact 39 to open, removing the short-circuit normally existing across resistance B. This short-circuited resistance B is provided 75

to compensate for the voltage drop caused by the sudden connection of the voltage regulator motor 14 upon operation of the relay 31. For example, if the unregulated voltage increases very slightly but sufficient to cause the relay 31 to be operated, the consequent connection of the voltage regulator motor 14 would increase the load sufficiently to cause a line drop in voltage equal to or greater than the initial increase, so that the regulator would be automatically rebalanced without any adjustment of the motor driven rheostat W. This would permit the release of the relay 31 and the disconnecting of the voltage regulator motor 14 which, upon removal of its load, would permit the line voltage to return to its initially increased amount. Consequently, for a slight increase in voltage, the only action would be a chattering of the relay 31 and the galvanometer G. R. without effecting any permanent adjusting. The sudden insertion of the resistance B by operation of the relay 31 causes the voltage at the terminal of the galvanometer relay connected to the point S to decrease an amount equal to the drop which would be caused by connection of the voltage regulator motor 14, so that the voltage difference across the galvanometer relay will be very nearly that which would be obtained if no load were put on the line by the voltage regulator motor 14.

It will also be noted that if the voltage changes sufficiently the motor driven rheostat W will reach its limit in one direction or another. While the regulator as described is operable to produce a constant regulated voltage from a source of electric potential varying over a wide range, it will not regulate over the entire range, and it is accordingly necessary to provide means for preventing mechanical injury to the rheostat and its driving mechanism. Limit switches are accordingly provided on the rheostat and arranged in such a manner that their circuits are opened before the mechanical limit of the rheostat is reached. These limit switches are shown at 40 and 41 for the relays 1 and 31 respectively. Opening of the limit switch 40 when the rheostat W has reached one limit of its motion disconnects the relay 1 by breaking its energizing circuit at the contact 4 of the limit switch, causing the voltage regulator motor 14 to stop. Similarly, opening of the limit switch 41 when the rheostat W has reached the other limit of its motion disconnects the relay 31 by breaking its energizing circuit at the contact 33 of the limit switch, likewise causing the voltage regulator motor 14 to stop. At the same time that the contact 4 of the limit switch 40 is opened, the contact 42 of the limit switch is closed, thus completing a circuit from positive terminal line E, through wires 7, 6 and 5, through contact 42, through wire 43, through a trouble bell 44 and a trouble lamp 45 in parallel, and through the wire 46 to negative line terminal O. Similarly, at the same time that the contact 33 of the limit switch 41 is opened, the contact 47 of the limit switch is closed, thus completing a circuit from positive terminal line E, through wires 7 and 34, through contact 47, through wires 48 and 43, through a trouble bell 44 and a trouble lamp 45 in parallel, and through the wire 46 to negative line terminal O. It will therefore be seen that trouble signals are given when the unregulated line voltage is too high or too low, i. e., beyond the adjusting range of the regulator, so that proper steps may be taken at once to correct the voltage directly at the source. A switch 49 is pro-

vided in the circuit of the trouble bell 44 so that the trouble bell may be stopped, but the trouble lamp 45 remains lighted until the trouble has been corrected.

The condensers 50 and 51 shown connected across the relays 1 and 31 respectively are used to reduce arcing of the contacts of the galvanometer relay G. R.

The resistance C of the voltage regulator is provided with an adjustable tap to compensate for differences in resistance of the commercially wound resistors A and B and also to permit adjustment of the regulating voltage due to differences in the voltage produced across each of the glow tubes G and T.

It will, of course, be understood that if the unregulated line voltage across the terminal lines E and O remains constant, and if the load connected across the terminals L₁ and L₂ of the regulated voltage changes sufficiently to alter the regulated voltage itself, the regulator arrangement will become unbalanced, and the regulator will operate to adjust the value of the resistance W so as to return the regulated voltage to its proper value.

It will accordingly be seen that the present invention not only provides a constant voltage across desired terminals despite variations of the voltage at the source of electric potential, but also despite variations in the load applied across said terminals.

Referring now to Figure 3, the arrangement here shown is similar to that shown in Figure 2, but the arrangement of Figure 3 will act to regulate a voltage only of a magnitude equal to the sum of the regulating voltages of the glow tubes G and T.

The arrangement of Figure 2, on the other hand, can be employed to produce a regulated voltage of a magnitude greater than the regulating voltage of one glow tube and less than the sum of the regulating voltages of two glow tubes. With this arrangement limited changes in the range of the regulated voltage are obtainable in view of the limited range of adjustment of the point S of the series of resistances Y.

Figure 4 shows another arrangement in accordance with the present invention, this arrangement being similar to that of Figure 2, but employing only a single glow tube T. With this arrangement it is possible to produce a regulated voltage of any magnitude greater than the regulating voltage of the glow tube but less than the unregulated line voltage. However, this arrangement is not quite as sensitive as that of Figure 2, because in Figure 4 the voltage at the point S changes with changes in the unregulated line voltage, whereas in Figure 2 the voltage at the point S remains absolutely constant despite changes in the unregulated line voltage, as already explained in connection with Figure 2. Limited changes in the range of the voltage to be regulated are also obtainable with the arrangement of Figure 4.

Figure 5 shows an arrangement for obtaining regulated voltages of a magnitude less than the regulating voltage of the glow tube with limited changes in the range of the voltage to be regulated, the resistance R connected across the glow tube N being suitably tapped to produce a regulating voltage less than the regulating voltage of the glow tube.

Figure 6 also shows an arrangement for obtaining regulated voltages of a magnitude less

than the regulating voltage of the glow tube but with wide changes in the range of the voltage to be regulated. As in Figure 5, the resistance R connected across the glow tube N is suitably 5 tapped to produce a regulating voltage less than the regulating voltage of the glow tube.

Figure 7 shows an adaptation of the present invention to controlling the output voltage of an electric generator, so as to maintain it constant. In Figure 7 the generator is shown at 10 52 and its output terminals at 53 and 54. The field 55 of the generator is connected to be energized from the output of the generator. At the same time a voltage regulating arrangement in 15 accordance with the present invention is connected across the output of the generator, and the galvanometer relay of the voltage regulating arrangement is connected to control the resistance of the field 55, so that any change in the 20 magnitude of the output voltage of the generator is communicated to the voltage regulating arrangement, which then causes the resistance of the field 55 to change in the proper direction for returning the output voltage of the 25 generator to its desired constant value, it being understood that the value of the output voltage of the generator is determined by the strength of its field, which in turn is determined by the field resistance.

30 In connection with Figure 7 it will be noted that batteries 56 have been shown as voltage regulators instead of the voltage regulating neon glow tubes described in connection with the previous figures. It will, of course, be understood 35 that batteries act to maintain a practically constant voltage and therefore may be employed interchangeably with the neon glow tubes or any other type of voltage regulating element, it being, of course, apparent that the regulating 40 effect of the present invention is based upon the use of a constant voltage regulating element.

It should, of course, be further understood 45 that commercially obtainable voltage regulating elements, such as neon glow tubes, pass only small currents, and will not act to regulate the voltage when connected directly across apparatus drawing a relatively large current.

Figure 8 shows an adaptation of the present 50 invention to controlling the speed of an electric motor, so as to maintain a constant speed. In Figure 8 the motor is shown at 57, and the motor field at 58, the motor field being connected to be energized by a source of electric potential subject to fluctuations in voltage. There is also 55 shown a relatively small output generator 59 connected to be driven by the motor 57, the arrangement constituting a motor-generator set. Across the output terminals of the generator 59 is connected a voltage regulating arrangement 60 in accordance with the present invention, the voltage regulating arrangement being connected to vary the resistance of the motor field 58. Assuming that the motor has been operating at a desired constant speed, and that the 65 voltage regulating arrangement has been balanced at the resulting output voltage of the generator, any change in the voltage energizing the motor, resulting in a change in speed of the motor, will result in a change in the output voltage 70 of the generator, which change will be communicated to the voltage regulating arrangement. The voltage regulating arrangement will then act to vary the resistance of the field of the motor in such a direction as to return the 75 speed of the motor to its desired constant value,

at which time the output voltage of the generator will return to its desired constant value, resulting in a return to normal of the voltage regulating arrangement.

From the foregoing detailed description of 5 various embodiments and applications of the present invention, it will be seen that I have produced decided improvements in electrical arrangements for obtaining a constant voltage from a source of electric potential subject to 10 fluctuations in voltage, and that I have accomplished the various objects set out at the beginning of this specification.
